Primary Examiner — T Chase Nelson

Assistant Examiner — Mary Claire Ramirez

(57) **CLAIM**

The ornamental design for a photo booth, as shown and described.

DESCRIPTION

FIG. 1 is a front perspective view of a photo booth showing our new design;

FIG. 2 is a rear perspective view thereof;

FIG. 3 is a left-side view thereof;

FIG. 4 is a front view thereof;

FIG. 5 is a right-side view thereof;

FIG. 6 is a rear view thereof;

FIG. 7 is a top view thereof; and,

FIG. 8 a bottom view thereof.

The broken lines shown in the drawings depict portions of the photo booth that form no part of the claimed design.

1 Claim, 8 Drawing Sheets
